(57) **CLAIM**

The ornamental design for a television receiver, as shown and described.

DESCRIPTION

FIG. 1 is a front perspective view of a television receiver showing my new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is a rear perspective view thereof;

FIG. 8 is a front perspective view showing the state in which the left part of the TV display has been curved;

FIG. 9 is a left side view thereof of FIG. 8;

FIG. 10 is a right side view thereof of FIG. 8;

FIG. 11 is a top plan view thereof of FIG. 8;

FIG. 12 is a bottom plan view thereof of FIG. 8;

FIG. 13 is a rear perspective view thereof of FIG. 8;

FIG. 14 is a front perspective view showing the state in which the left part and right part of the TV display has been curved;

FIG. 15 is a left side view of FIG. 14 where the right side view is a mirror image;

FIG. 16 is a top plan view thereof of FIG. 14;

FIG. 17 is a bottom plan view thereof of FIG. 14; and,

FIG. 18 is a rear perspective view thereof of FIG. 14.

The broken lines depict portions of the television receiver that form no part of the claim.

1 Claim, 15 Drawing Sheets
